SWITCH

Leonard R. Carley, Watertown, and Reid B. Scott, Waterbury, Conn., and Horace L. Allen, New York, N. Y.

Original application August 27, 1929, Serial No. 388,668. Divided and this application August 2, 1930. Serial No. 472,690

2 Claims. (Cl. 200—87)

Our invention relates to new and useful improvements in electric switches, and the present application is a division of one filed by us on August 27, 1929, Serial No. 388,668, for Automatic electric signalling devices.

An object of the invention is to provide a new and novel switch that is especially adapted to be combined with a form of semi-automatic control to be used on a motor vehicle in conjunction with certain warning lamps, so that one of two rear lights (not shown) might be lighted by pressing respective buttons. Thus, a vehicle to the rear may be notified at a distance before an approach to a turn when the system automatically functions.

Still another object of the invention is to provide a magnetic switch so that when the switch is properly wired in an electric warning system, when one circuit is closed, it will energize one magnet which may light one or two rear lights and wherein when the other circuit is closed, a second magnet will be energized, these circuits being, in turn, partly controlled by a switch arm on the steering post of the vehicle.

Still another object of the invention is to provide a small electrical switch which may be operated by two control buttons (not shown) and which switch may be readily attached to any form of motor vehicle and then conveniently wired to two rear lights and the steering gear, so that the warning may be flashed to any vehicle in the rear to show the intended course of the driver.

Still another object of the invention is to provide a switch in the form of a unit that may be cheaply manufactured and easy to assemble and may be quickly installed in the system as outlined in the parental application above mentioned or may be used on other circuits that may conveniently be opened or closed by a magnetically-operated switch of this type.

With these and other objects in view, the invention consists in certain new and novel arrangements and combination of parts, as will be hereinafter more fully described and pointed out in the claims.

Referring now to the drawing showing a preferred embodiment,

Fig. 1 is a front elevation of the switch, a portion of the cover being broken away for the sake of clearness;

Fig. 2 is a side elevation partly in section;

Fig. 3 is a top plan view;

Fig. 4 is a perspective of the upper contact member with its plurality of spring members.

Referring now more particularly to the drawing and for the moment to Fig. 1, there will be seen a small dielectric panel 17, on which are mounted two magnetic coils 10 and 11.

It will be understood that we have shown these of relatively great length and the respective iron cores 18 and 19 projecting beyond the respective wire winding. However, much shorter magnetic coils with their iron cores might be equally as well utilized to thus condense the switch and, therefore, occupy less space under the dash or whatever it is desired to fasten same.

To the rear of the panel is secured a metal strip 18^a so that this switch may be conveniently bolted to any part of the car desired. There is also shown an outer cover plate 19^a which covers the magnet coils 10 and 11, which cover may terminate short of the top of the panel 17, so that the upper part of the switch is accessible, although, if desired, the whole switch might be fitted within a casing or cover so as to be foolproof.

Located above the two coils, there is shown an insulated bar of hard rubber or fiber 20, which may be of the same material as the panel and cover; while directly above the two respective coils, there are drilled in the bar the openings 21 and 22, so that the respective plungers 23 and 24 may be slidably placed therein.

Looking at the plunger 23 for the moment, which is identical with the other one, there will be seen a small head or face 25, which is adapted to be drawn towards the core 18 of the coil 10 when the coil is energized.

The upper end of the plunger 23 is threaded, and fitted thereon is a small cross bar 26, which is adjusted by the nut 27 and then held in its adjusted position by the lock nut 28.

In the same manner, the plunger 24 has the like cross bar 29, adjustable nut 30 and the lock nut 31.

Located near the top of the panel and above the bar 20 is the small strip of metal 32, as shown in Fig. 5. This strip is provided with the fingers 33 and 33', 34 and 34'. These fingers project upwardly at the outer ends, as may be clearly seen, and inasmuch as the strip and fingers are cut from a brass plate, the fingers are flexible, so that they can be respectively forced downwardly when the plungers are actuated and will return to their normal position when the plunger returns. The strip 32 may be riveted or bolted in position through the provision of the small holes 35.

110

It will be noticed that the cross bar 26 extends across the fingers 33 and 33' while the cross bar 29 extends across the fingers 34 and 34', so that each cross bar actuates two of the fingers.

Located in the bar 20 are the electric contacts 36, 37, 38 and 39, so that when the fingers 33 and 33' are depressed by the magnetic action of the coil 10 through the downward movement 10 of the plunger and cross bar, these fingers, in turn, will contact with the connections 36 and 37, and likewise when the fingers 34 and 34' are depressed through the action of the coil 11 and its plunger, the fingers 34 and 34' will be in contact with the latter-mentioned contacts 38 and 39.

In Fig. 1, these electric contacts may be clearly seen, while from each of these contacts will extend a lead wire to its cooperating part when 20 used in a system as shown in the parental application.

To the strip 32, there extends a lead wire 49 and we have shown this connected right across the top of the strip, although from an electrical 25 standpoint, it may simply be connected to the metal strip itself.

By using this flexible metal strip 32 and integral flexible fingers, it does away with the necessity of having tension springs about each 30 of the plungers, so that normally there is no contact between the cores and the ends of the plungers or the contacting fingers, but if desired any suitable form of compressible springs and contacts may be used. It will be understood 35 that after either plunger is operated, the respective fingers will remain depressed as long as the coils are energized, but will immediately return to their normal position when the magnetic influence has been broken.

As heretofore mentioned, the way the switch is wired in the circuit with which it is to be used is fully shown in the parental application, but for the sake of clearness, it might be here 45 mentioned that the four fingers 33, 33', 34 and 34' are all connected by the wire 40 and there is a connection 55 from the bottom of the coil up to the finger 38 and there may be a small wire 56 from which may extend a wire 56 to a part of the circuit. Also, the magnet 11 is connected 50 to the coil 10 at its bottom and there is a connection from the bottom of the magnet 52 up to the connection 37 from which may lead a small wire 53. The last finger will be connected by a lead wire 57.

As is here shown, the magnetic switch is a unit and although it is designed for certain circuits, it will be seen that other circuits might be operated by the switch.

It will also be understood that although we have shown the switch having a front panel in

the form of a cover, the entire unit might be encased in a different form of covering, so that it will be fool-proof and dust-proof.

From the foregoing, it will be seen that we have produced an electric switch of simple construction having two magnetic coils therein and wherein certain circuits are closed when certain fingers are depressed and wherein certain circuits are closed when other fingers are depressed and wherein both automatic and semi-automatic circuits may be used. Furthermore, the fingers are all formed from an integral strip and will give long and constant service.

It will be understood that in this case we have not set out the wiring system in which the switch is to be used, as this is fully disclosed in the parental case but we have, on the other hand, described the construction and arrangement of the parts of the switch and have also set out how the several parts of the switch are wired to form the unit.

Having thus described our invention, what we claim as new and desire to secure by Letters Patent is:—

1. A magnetic switch for warning signals, including a support, means extending from the support for holding slidable plungers, slidable plungers in said means and each plunger adapted to be actuated by a magnetic coil, electric contacts, flexible circuit-carrying fingers secured to said support and extending downwardly and outwardly and slightly upwardly at their outer ends and positioned directly above said respective electric contacts, each of said plungers provided with an adjustable cross-head resting on the outer upward extending portions of two of said flexible fingers and forcing the outwardly extending portion of said fingers downwardly against their respective electric contacts when said plunger is actuated.

2. A magnetic switch for warning signals, including a support, a shelf extending from the support, slidable plungers mounted on said shelf, each plunger adapted to be actuated by a magnetic coil, a circuit-carrying plate mounted above said shelf and consisting of a plurality of circuit-carrying spring fingers, electric contacts mounted on said shelf directly beneath the respective circuit-carrying fingers, each of said plungers provided with an adjustable cross-head and the said cross-head resting on two of the respective fingers and normally holding the cross-head and plunger in an upward position and the cross-head forcing the fingers in contact with the electrical contacts when the cross-head is moved by its plunger.
